UNITED STATES PATENT OFFICE.

CHARLES S. FITZGERALD, OF DES MOINES, IOWA.

PRINTER'S ANGLE-FURNITURE UNIT.

Application filed August 6, 1928. Serial No. 297,618.

My present invention has for its object to provide printer's angle furniture in a two-part unit of very simple and inexpensive construction for convenience in quickly 5 and easily locking printer's forms in a chase at various angles.

More particularly, it is my object to provide such a two-part furniture unit comprising respectively an element substantially 10 triangular in outline, having two faces arranged at right angles to each other and having in the hypotenuse of the triangle a concave-faced portion, curved substantially on the arc of a true circle. The other element 15 of the unit is a member made substantially in the form of a half of a circular disc of substantial thickness with its curved face adapted to fit the concave face in the first element.

With these and other objects in view, my 20 invention consists in the construction, arrangement and combination of the various parts of my angle furniture unit, whereby the objects contemplated are attained, as 25 hereinafter more fully set forth, pointed out in my claims, and illustrated in the accompanying drawings, in which:

Figure 1 is a plan view of a printer's 30 chase with a lock-up for a form therein employing my improved furniture.

Figure 2 is a detail, vertical, sectional view taken on the line 3—3 of Figure 1, showing in section both elements of my furniture unit and a quoin of standard construction; and

Figure 3 is a perspective view of the two elements of my furniture unit.

In the drawings herewith, I have used the reference numeral 10 to indicate generally a 40 printer's chase. Received within the chase is an ordinary rectangular form 12 arranged with its axis at a substantial angle with relation to the inner walls of the chase.

It is a difficult matter to lock such a form 45 at such an angle in the chase, so that it will not slip under the conditions ordinarily found when the form is used in a printing press. Yet it becomes necessary in the printing industry to lock forms in chases at 50 a great variety of angles.

For purposes of illustration, I have shown the form 12 used with a plurality of my furniture units.

It will be noted that the usual furniture 55 (not now referring to my particular units)

comprised of blocks 14, 15, 16, 17, 18, 19, 20 and 21 is used for building out from the walls of the chase.

My improved unit comprises two elements indicated in Figure 3 by the reference 60 characters A and B.

The furniture unit element A is in the form of a block substantially triangular in outline with two faces 22 and 24 arranged in planes at right angles to each other. The 65 face of the element A, which is, as one might say in the hypotenuse of the triangle, is curved as indicated at 26 on the curvature of a circle. For instance, the arc taken any place in the horizontal plane on the element 70 A would extend from near the face 22 to near the face 24, as shown in Figure 3.

The other element of the unit comprises a block B in the form of a half of a circular disc of the same height or thickness as 75 the block A.

The curved face of the element B fits the face 26 of the element A.

The top of the element A may be provided with graduation marks 27 and the top of the 80 element B may be provided with an indicating arrow 29 midway of the length of its curved face.

In Figure 1, I have shown several of my units arranged in different positions to show 85 the various ways in which the unit can be employed.

For instance at the upper right-hand corner of Figure 1, I have shown the member A of one of the units arranged with one 90 face against the furniture member 21 and the other member against the side wall of the chase. The flat, vertical face of the unit member B fits against the end of the form 12, and the curved faces of the members A and B fit together, as shown. The unit now under consideration, I have indicated generally by the reference character a.

I have indicated another unit at b with the member B arranged with its flat vertical 100 face against the face of a rectangular piece of printer's furniture member 30 and with the member A arranged with one face against the furniture member 20 and the other against an ordinary quoin 28 arranged 105 between the element A and the furniture member 19.

At c, I have shown another one of my elements, with the member A in the corner formed by the wall of the chase, and the fur- 110

niture member 18, and with a quoin 28 interposed between the member element B and the furniture member 30.

At the opposite end of the form from the unit shown at *a* is a unit indicated at *d*, showing a slightly different arrangement in which my unit may be used. Adjacent the side of the form opposite the member 30 is a similar furniture member 30^a.

10 One of my units as shown at *e*, together with another quoin 28 is arranged between the furniture member 30^a and the corner formed by the furniture members 15 and 16.

As shown at *f*, still another of my units is 15 arranged near the opposite end of the member 30^a between that member, the side wall of the chase, and the end of the member 14.

A quoin 28 is interposed between the element A and the member 14.

20 With this style of furniture unit, there is provided a printer's lock-up, by which much time is saved in locking diagonal forms in a chase. The time necessary for securing accurate registration is considerably reduced.

25 My improved unit is thick enough and sturdy enough to permit the rigid locking of the form in any possible position.

The form can be locked at any angle with 30 relation to the walls of the chase without any tendency of the unit members A and B to slip or rotate with relation to each other.

35 The units are so arranged that if the unit B is rotated slightly with relation to the unit A, there remains ample bearing surface for taking pressure directly at right angles to the side face or edge of the form. Thus it is convenient to lock a form arranged at an angle to the walls of the chase by means of these units, together with other furniture 40 between the units and the sides of the chase with one or more quoins for adjustment.

45 My angle furniture unit may be placed on all four sides of a form, but quoins are actually needed only on two sides. If quoins are used on all four sides, this will facilitate easy and speedy securing of accurate register, since any quoin can be adjusted by expanding or contracting, when used with my

units, and the parts can be quickly adjusted to proper position. 50

The graduations on the elements will indicate the movement of the form and thus eliminate guess work.

It will be noted that my improved angle furniture unit will function equally well 55 with the quoin in front or behind the unit.

The advantage of placing the quoin behind the unit is in bringing the type form closer to the rim of the chase when necessary. 60

I prefer to use the Notting quoin in conjunction with my angle furniture as it allows free action and has a straight forward shove without any right or left give. This is important in an angle form for registering 65 color work and so forth.

I claim as my invention:

1. A printer's angle furniture unit comprising a pair of elements, one of said elements comprising a block of substantial 70 thickness, substantially triangular in outline with two faces arranged in planes at right angles to each other, and a third face on the hypotenuse side of the triangle curved on the arc of a circle, and a second element in the form of a portion of a disc of substantial thickness having a curved 75 face corresponding with the curved face of the first unit.

2. A printer's angle furniture unit comprising a pair of elements, one of said elements comprising a block of substantial thickness, substantially triangular in outline with two faces arranged in planes at right angles to each other, and a third face on the 80 hypotenuse side of the triangle curved on the arc of a circle, and a second element in the form of a portion of a disc of substantial thickness having a curved face corresponding with the curved face of the first 85 unit, one of said units having on its top surface graduation marks and the other having an indicating mark. 90

Des Moines, Iowa, June 15, 1928.

CHARLES S. FITZGERALD.
